Eugene T. Turner,
Inventor,
By his Attorney,
Mitchell & Alley,

UNITED STATES PATENT OFFICE.

EUGENE T. TURNER, OF NEW YORK, N. Y., ASSIGNOR OF ONE-HALF TO ERNEST C. WILCOX, OF MERIDEN, CONNECTICUT.

SOUND REPRODUCING AND RECORDING APPARATUS.

1,306,131.

Specification of Letters Patent. Patented June 10, 1919.

Application filed January 4, 1919. Serial No. 269,559.

To all whom it may concern:

Be it known that I, EUGENE T. TURNER, a citizen of the United States of America, residing at New York city, county and State of New York, have invented a new and useful Sound Reproducing and Recording Apparatus, of which the following is a specification.

My invention relates to improvements in sound reproducing and recording apparatus. The main object is to provide certain improvements in construction whereby sounds may be reproduced or recorded with great fidelity as to detail and quality. Another object is to provide an improved construction whereby the volume of sound reproduced may be intensified without sacrifice to quality. Other objects and advantages will be apparent to those skilled in this art from a reading of the following description and an examination of the accompanying drawing, in which I have conventionally shown the apparatus in one preferred form, it being obvious that the same may be modified in various ways without departure from the spirit or scope of my invention.

In the drawings:

Figure 1 is a plan view of an apparatus constructed to embody my invention.

Fig. 2 is a relatively enlarged sectional view thereof on the line 2—2 of Fig. 1.

Fig. 3 is a relatively enlarged sectional view on the line 3—3 of Fig. 1.

Fig. 4 illustrates a modified detail.

1 represents a diaphragm. 2 is a back having a sound passage 3. 4 is a flanged annulus secured to the back preferably in such a manner as to clamp the diaphragm 1 securely in place. 5—5 represent two bushings for suitably holding the edge of the diaphragm. 6 is a vibratory needle bar fulcrumed at 7. 8 is a bar or bridge preferably of wood or wood-like material which extends over the needle bar and is supported upon the diaphragm within the field of vibration. The bridge 8 is preferably supported on the diaphragm at two points as by the bridge ends or posts 9—9 also preferably of wood, which latter may be secured to the diaphragm in any suitable way as by screws 10—10. 11 is a connection preferably of flexible catgut which serves to connect the end of the needle bar with the diaphragm 1 and with the bridge bar 8. In the particular form shown, the inner end of the con-

nexion 11 is passed through the diaphragm and knotted underneath the same. The middle portion of the connection 11 is wrapped around or otherwise suitably fastened to that part of the needle bar directly above the connection with the diaphragm. The outer end of the connection 11 is secured to the bridge 8 preferably by means of an adjusting screw 12 which is carried by the bridge and by which the tension of the connection 11 may be regulated. In this particular instance, the screw 12 is hollow and the outer end of the connection 11 is passed through the same and knotted. If desired, the connection 11 when made of catgut or any material affected by moisture, may be covered with water-glass to protect the same and to also stiffen that part wrapped around the needle so that it will not work loose. The bridge 8 should, of course, be connected to the diaphragm in such a position relatively to the nodal points thereof as to not materially interfere with the vibrations of said diaphragm, and the proper location may be determined by trial until the best results are secured with the particular diaphragm used. Obviously, when diaphragms of uniform dimensions are determined upon and used, the proper setting of the bridge in one case will practically determine the setting in all cases.

In operation, and for the purposes of reproducing sound, the needle or point 14 carried at the outer end of the needle bar may be set down into a record groove so that as the point trails through said groove, the undulations therein will oscillate the needle bar so as to vibrate the diaphragm through the medium of the connection 11. It will be observed that the movement of the inner end of the needle bar both to and fro exerts a pulling strain on the connection 11, and hence, the flexing of the diaphragm in both directions is produced solely by the pull of the needle bar rather than by a direct and positive push and pull movement such as commonly in vogue. I attribute the successful operation of the instrument in a very substantial measure to the aforesaid operation of said connection, and when the bridge is made of wood and the connection is made of catgut or the like, the sounds reproduced seem to possess qualities which most closely approximate the true quality of the sounds recorded and which it is sought to repro-

duce. While I have described my invention chiefly as a sound reproducing device, it will of course be understood that the same means may be used for producing a groove, on the 5 wall or walls of which sound waves are to be recorded by minute undulations, and it is my intention that the following claims are to be of such scope as to cover said apparatus whether the same is used for one purpose or 10 the other.

9^a, Fig. 4, represents one of the feet shown in Fig. 3, by means of which the bridge is connected or put in contact with the diaphragm, the lower end of the foot in this 15 case being tapered so as to afford substantially a line contact with the diaphragm instead of a contact of substantially more area, such as shown in the previous figures. In some instances, the holding screws 10—10 20 may be omitted since the tension of the connector 11 may be sufficient to hold the bridge in contact with the diaphragm. Obviously, as to such details I contemplate that many modifications may be made.

25 What I claim is:

1. In an instrument of the character described, a diaphragm, a vibratory needle bar wholly on one side of said diaphragm, a flexible connection between said bar and said 30 diaphragm whereby a pulling movement upon said connection will positively flex said diaphragm in both directions.

2. In an instrument of the character described, a diaphragm, a vibratory needle bar, 35 a flexible connection between said bar and said diaphragm whereby a pulling movement upon said connection will positively flex said diaphragm in both directions, said connection including a bar overstanding 40 said needle bar and diaphragm and mounted upon the latter within the field of vibration.

3. In an instrument of the character described, a diaphragm, a vibratory needle bar, a flexible connection between said bar and

said diaphragm whereby a pulling movement upon said connection will positively flex said diaphragm in both directions, said connection including a bar overstanding 45 said needle bar and diaphragm and mounted at two points upon the latter within the field 50 of vibration.

4. In an instrument of the character described, a diaphragm, a bridge mounted at a plurality of points thereon within the field of vibration, a vibratory needle bar, one end 55 of the same being located between said bridge and said diaphragm and a flexible connection between the end of said needle bar and the bridge and the diaphragm.

5. In an instrument of the character described, a diaphragm, a vibratory member, a device overstanding said member and in contact with said diaphragm within the vibrating field thereof, and a connection from 60 said member to said diaphragm and to said device, whereby the impulses of said vibrating member will be transmitted to said diaphragm.

6. In an instrument of the character described, a diaphragm, a vibratory member, a bridge overstanding said vibratory member and mounted upon said diaphragm at opposite sides of said member and within the vibrating field of said diaphragm, and a connection from said member to said diaphragm 75 and to said bridge whereby the vibratory impulses of said member will be transmitted to said diaphragm directly and also through the medium of said bridge.

7. In an instrument of the character described, a diaphragm, a vibratory member adjacent said diaphragm, a bridge mounted on said diaphragm and overstanding said member and an adjustable flexible connection from said member to said diaphragm 80 and to said bridge.

EUGENE T. TURNEY.
